VENTILATED BUFFING WHEEL

Victor Lloyd Richards, Toronto, Ontario, Canada,
assignor to Canadian Hanson and Van Winkle
Company Limited, Toronto, Ontario, Canada, a
corporation of Canada

Application September 22, 1950, Serial No. 186,133
In Canada January 7, 1950

3 Claims. (Cl. 51—193)

1

This invention relates to buffing wheels and in particular to ventilated buffing wheels.

In the use of buffing wheels for finishing and/or polishing articles, the buffing wheel is rotated at a very high speed and the work forced against it by the operator with such pressure as may be required to produce the desired result. A suitable abradant or polishing material usually intermingled with a suitable carrying vehicle, such as a lubricant, is generally applied to the periphery of the wheel. The friction produced by the contact of the rapidly rotating periphery of the wheel with the work produces very considerable heat which in some instances is sufficient to char the fibres of the buffing material at the periphery of the wheel.

Heretofore attempts have been made to provide means for cooling buffing wheels by circulation of air between the sections of the buffing wheels by mounting the buffing wheel sections upon a hollow shaft having a port or ports leading to the spaces between the sections of the buffing wheel, as disclosed in United States Patent No. 1,573,961, but in such constructions the sections of the buffing wheel are so closely clamped together between collars upon the shaft that a sufficiently rapid circulation of air is not obtained to accomplish the desired result.

The cooling of buffing wheels has also been accomplished by means disclosed in United States Patent No. 1,922,108, now Reissue 19,894, in which the buffing wheel comprises a series of annular buffing units which are gathered at their inner edges to produce radially extending folds or ridges, the inner circumference of the annular buffing strips being held by a ring-shaped metal binding strip having toothed edges bent inwardly toward each other so as to clamp the layers of cloth together, the rings being also provided with legs or projections which in the assembled wheel separate the units from each other and provide radial passages between them for the air coming from the ventilated supporting hub or center. In this construction also the annular strips or layers of buffing material are provided at intervals with aligned apertures through which the air enters at a distance from the periphery of the buffing wheel and by virtue of the centrifugal action is discharged between the sections at the periphery of the buffing wheel.

An improvement over the buffing wheel construction of United States Patent No. 1,922,108 is described in United States Patent No. 2,140,208. In the latter patent, the annular strips have no

2

aligned apertures and the ring-shaped metal binding strip has no legs or projections to separate the buffing units from each other. There is provided instead a ventilated supporting hub or center which has a peripheral flange supporting the buffing units and having slots cut into it so as to form with the metal binding strips radial passages between the units for the air coming from the hub or center.

10 The particular constructions described in the last two mentioned patents have several disadvantages. The spaces or hub is designed for use with the one particular buffing unit or at least a buff edged with steel. Thus other types 15 of buffs cannot be used to advantage with this hub. In addition, the annular clamping rings are likely to be broken when the wheel is run at high speeds and when so broken will be projected outwardly with great force, thereby endangering the operator to serious injury.

In United States application Serial No. 62,739, filed on November 30, 1948, in the name of Victor L. Richards, now United States Patent No. 2,526,420, a ventilated buffing wheel assembly 25 is described which overcomes the foregoing disadvantages. This assembly comprises buffing units preferably formed of a plurality of plies of flexible material and possessing radial furrows and being reinforced near their inner edge by a 30 ring, said ring being held in place and said furrows being formed by folding and stitching of the plies over said ring, and ventilated supporting hubs or centers having slots cut into their periphery together with a flanged ring and a plain annular ring attached on opposite sides of 35 said periphery so as to support the buffing units and form with said slots a radial air passage between them.

Although this ventilated buffing wheel assembly is a definite improvement over the assemblies of the prior art in that the hub or spacer thereof provides radial air passages between the buffing units independently of the construction of such units and is thus adaptable for use with 45 various types of buffing units, it nevertheless has several disadvantages. For instance, since the hub or spacer consists of three pieces which must be attached together and the center piece must have slots cut into its periphery, the manufacture 50 of this hub or spacer requires much time and expense. Furthermore, the radial air passages formed by those three pieces are of such size as to be easily crushed by the pressure exerted by the lathe spindle nuts of the assembly and easily blocked by lint and dirt. In addition,

tion, since the hub or spacer is smooth on both sides, there is a tendency for the buffering units to slip thereon thus causing frictional heat between the unit and the hub or spacer.

It is an object of this invention to provide an improved ventilated buffering wheel assembly which has none of the disadvantages of the foregoing assembly while permitting the same sufficiently free circulation of air to properly cool the buffering wheel. Another object of this invention is to provide a spacer or hub to be used in such assembly. Other objects of this invention will be obvious from the following description of the invention.

These objects are accomplished by providing a hub or spacer more or less in the shape of a flanged wheel, consisting of a disc having a plurality of radial flutes stamped at intervals in its outer periphery and extending inwardly from the peripheral edge and a central aperture to receive a spindle and a plurality of perforations radially disposed with respect to said aperture to form axially extending air passages, and a flanged ring attached between the spaced radial flutes to one side of said disc adjacent the outer periphery and overlaying the flutes, the depth of said ring from the outer edge to the inner edge thereof extending inwardly a smaller distance radially of said disc than the inward extent of said spaced radial flutes and thus defining with said flutes radial air passages. This hub or spacer is adaptable for use with various types of buffs but in particular with a buff possessing radiating furrows which are formed by folding a plurality of plies of flexible material cut on the bias over a ring and stitching in order to hold the ring in place and gather the plies into radiating furrows.

A particular embodiment of this invention may be described with reference to the drawings in which

Figure 1 is a front elevation of the fluted disc of the hub.

Figure 2 is a sectional view of the fluted disc of the hub along lines 2—2 of Figure 1.

Figure 3 is an enlarged view of the flutes of the disc.

Figure 4 is a front elevation of the flanged ring of the hub.

Figure 5 is a sectional view of the flanged ring of the hub along lines 5—5 of Figure 4.

Figure 6 is a front elevation of the hub.

Figure 7 is a sectional view of the hub along lines 7—7 of Figure 6.

Figure 8 is a front elevation of the preferred pucker buffering unit.

Figure 9 is a sectional view of the buffering wheel assembly.

As is shown in Figures 1 to 7 inclusive the hub or spacer is made of two parts, a center plate or disc 1 and a flanged ring 2 appropriately fastened together, for instance, by spot welding. The center plate 1 is provided with a flanged central aperture 3 for receiving a spindle. In addition it is provided with a plurality of perforations 4, radially and uniformly disposed with respect to the central aperture 3. A plurality of flutes 5 are stamped at intervals in the periphery of the central plate 1 and extend inwardly from the peripheral edge. These flutes 5 together with the flanged ring 2 form passages for delivering air outwardly from the central portion during the revolutions of the wheel.

Figure 8 shows the preferred buffering unit which is formed of a plurality of plies 6 of cotton cut

on the bias and doubled along the solid steel ring 7 and gathered by stitching 8 in order to hold the plies in place and in order to form the radiating folds 9. The folds 9 together with the grooves 5 in the hub form the complete ventilating passages.

Figure 9, which shows a sectional view of a buffering wheel assembly, illustrates how the buffering unit fits over the flange of the hub or spacer. As in the other figures 1 indicates the central plate, 2 the flanged ring, 5 the flutes, 6 the plies of cloth, 7 the ring as stiffening member in the buffering wheel. The lathe flanges are indicated by 10 and aperture 11 in these flanges are designed to permit the entrance of air into the central portion of the assembly. Under operating conditions air is drawn into the centre of the assembly through the air passages formed by the perforations 4 and forced out through flutes 5 and furrows 9 to the periphery by the centrifugal force of the spinning buffering wheel assembly.

Although the buffering unit which is preferred is as described above, other types of buffs may be used with the hub or spacer which forms part of the invention. Thus the furrowed buffering unit described in U. S. Reissue 19,894 would serve. Even buffs possessing no furrows might be employed since radial furrows while advantageous are not essential in a ventilated buffering wheel. Such unfurrowed buffs might be those made of plies stamped from sheeting and either held loosely in the buffering assembly or sewn spirally, crosswise or radially prior to using. Buffs might also be made of small pieces of remnant cotton, sewn together into what is known in the trade as "pieced buffs."

In the preferred buffering unit the plies are made of a strip of cotton which has been cut on the bias. In this way every thread in the material forms an angle of 45° with the tangent at the point where the thread reaches the periphery. A buffering unit so constructed wears much longer than one made of plies which have merely been stamped from sheeting.

Moreover, it can readily be seen that the use of a solid ring in this buffering unit avoids the danger of flying apart during operation.

The preferred flexible material out of which buffs are made is cotton, but other textile materials and such materials as paper textile linters bonded with a suitable adhesive are known to make satisfactory buffering units.

The material out of which the hub may be made is preferably steel because of its cheapness and the ease with which the parts of hub can be made from it. However, any suitable metal, wood, cardboard or composite board might be employed.

In addition the flutes stamped at intervals and extending from the peripheral edge of the centre plate or disc need not be uniformly distributed about the periphery.

The advantages which this invention has over those of the prior art are several. For example, the hub or spacer need not be used with the buffering unit described above but may be used to mount other types of buffs. Moreover, it is not necessary for such buffs to be edged with steel since with this hub the radial air passages are formed as an integral part of the hub instead of relying on the steel edging to form two sides of these air passages. Furthermore, since the radial air passages are small and their entrance somewhat streamlined, there is less likelihood of them being crushed by the pressure exerted by the

lathe spindle flanges and blocked with lint and dirt.

The tendency of the buffing unit to slip on the hub or center with a resultant production of frictional heat is also minimized by the localized areas of high pressure which are created by the outer surface of the flutes in the periphery of the hub. Finally, the buffing wheel assembly formed by the above described hub and the preferred buffing unit is much cheaper and also .10 much stronger, and hence much safer than other prior art buffing wheel assemblies.

It will be readily understood that many modifications of the above described embodiment of this invention may be made without departing from the spirit of the invention and hence fall within the meaning and scope of the appended claims.

Having thus described my invention what I claim is:

1. A ventilated buffing wheel assembly comprising a plurality of annular buffing sections of flexible material arranged side by side; a spacing and supporting hub for each of said sections comprising a disc having a central aperture to receive a spindle and a plurality of perforations radially disposed with respect to said aperture to form axially extending air passages and a plurality of radial flutes stamped at intervals in the outer periphery of said disc and extending inwardly from the peripheral edge of the disc, and a ring attached between the spaced radial flutes to one side of said disc adjacent the outer periphery and overlaying said flutes, said ring having an axially extending flange centering and supporting said annular buffing section, the depth of said ring from the outer edge to the inner edge thereof extending inwardly a smaller distance radially of said disc than the inward extent of said spaced radial flutes and thus defining with said flutes radial air passages; and means clamping said sections and hubs for rotation with a spindle as a unit, said means having perforations therethrough to permit ingress of air.

2. In a ventilated buffing wheel assembly, an annular buffing section of flexible material and a supporting hub for said section comprising a disc

having a central aperture to receive a spindle and a plurality of perforations radially disposed with respect to said aperture to form axially extending air passages and a plurality of radial flutes stamped at intervals in the outer periphery of said disc and extending inwardly from the peripheral edge of the disc, and a ring attached between the spaced radial flutes to one side of said disc adjacent the outer periphery and overlaying said flutes, said ring having an axially extending flange centering and supporting said annular buffing section, the depth of said ring from the outer edge to the inner edge thereof extending inwardly a smaller distance radially of said disc than the inward extent of said spaced radial flutes and thus defining with said flutes radial air passages.

3. A ventilated buffing hub comprising a disc having a central aperture to receive a spindle and a plurality of perforations radially disposed with respect to said aperture to form axially extending air passages and a plurality of radial flutes stamped at intervals in the outer periphery of said disc and extending inwardly from the peripheral edge of the disc, and a ring attached between the spaced radial flutes to one side of said disc adjacent the outer periphery and overlaying said flutes, said ring having an axially extending flange for centering and supporting an annular buffing section of flexible material, the depth of said ring from the outer edge to the inner edge thereof extending inwardly a smaller distance radially of said disc than the inward extent of said spaced radial flutes and thus defining with said flutes radial air passages.
